US0D1015489S

(12) **United States Design Patent** (10) **Patent No.:** **US D1,015,489 S**
(45) **Date of Patent:** **** Feb. 20, 2024**

(54) **SHOWER HEAD**

(71) Applicant: **Lianfa Wang**, Zhejiang Province (CN)

(72) Inventor: **Lianfa Wang**, Zhejiang Province (CN)

(73) Assignee: **Wenzhou Dinggu Technology Co., Ltd.**, Zhejiang Province (CN)

(**) Term: **15 Years**

(21) Appl. No.: **29/787,668**

(22) Filed: **Jun. 8, 2021**

(51) LOC (14) Cl. **23-01**

(52) U.S. Cl.

USPC **D23/238**

Primary Examiner — Samantha Wood

(57) **CLAIM**

The ornamental design for a shower head, as shown and described.

DESCRIPTION

FIG. 1 is a perspective view of a shower head showing my new design;

FIG. 2 is a front elevational view thereof;

FIG. 3 is a top plan view thereof;

FIG. 4 is a left side elevational view thereof;

FIG. 5 is a rear elevational view thereof;

FIG. 6 is a right side elevational view thereof; and,

FIG. 7 is a bottom plan view thereof.

The broken lines in the drawings illustrate portions of the shower head that form no part of the claimed design.
